(57) **CLAIM**

The ornamental design for a trunk cover with slide-out workspace panels, as shown and described.

DESCRIPTION

FIG. 1 is a perspective view of a trunk cover with slide-out workspace panels in an electrical vehicle, in a closed position;

FIG. 2 is a perspective view thereof in an electrical vehicle, in an open position with the workspace panels collapsed; and,

FIG. 3 is a perspective view thereof in an electrical vehicle, in an open position with the workspace panels expanded. The broken lines showing a vehicle and the trunk cargo storage area illustrate environmental structure which form no part of the claimed design. The broken lines on the trunk cover with slide-out workspace panels depict portions of the article which form no part of the claimed design.
